CHARLES F. KETTERING, OF DAYTON, OHIO, ASSIGNOR TO DELCO-LIGHT COMPANY,
OF DAYTON, OHIO, A CORPORATION OF DELAWARE.

INTERNAL-COMBUSTION ENGINE.

Original application filed April 1, 1918, Serial No. 225,902. Divided and this application filed March 5, 1920. Serial No. 363,440.

To all whom it may concern:

Be it known that I, CHARLES F. KETTERING, a citizen of the United States of America, residing at Dayton, county of Montgomery, and State of Ohio, have invented certain new and useful Improvements in Internal-Combustion Engines, of which the following is a full, clear, and exact description.

10 This invention relates to power plants including an internal-combustion engine and has for its principal object the provisions of improvement in the construction of the plant, and more particularly in the construction of the engine.

This application is a division of my co-pending application Serial No. 225,902, filed April 1st, 1918.

It is an object of the present invention 20 to provide an oil deflecting device for preventing oil, which is thrown by oil throwing devices, being carried into the explosion chamber of an engine.

Further objects and advantages of the 25 present invention will be apparent from the following description, reference being had to the accompanying drawings, wherein a preferred form of one embodiment of the present invention is clearly shown.

30 In the drawings:

Fig. 1 is a view taken on the flywheel end of an engine, certain parts being broken away for the sake of clearness; and

Fig. 2 is a perspective view on a large 35 scale of a baffle screen.

Referring to the drawings, 20 indicates an internal-combustion engine having a crank case 21 providing a chamber and mounted upon a base 22. Crank case 21 is provided with an end cover 21^a. A cylinder 23, is mounted upon the crank case, supporting a cylinder head 24, which is provided with an explosion chamber 25. Cylinder head 24 has an inlet passage 26 and an exhaust passage 27 which lead into the explosion chamber 25. A flat partition 28 is provided which is apertured and forms a passage for communication between chamber 25 and passages 26 and 27, and which serves 50 as a seat for intake valve 29 and exhaust valve 30.

A crank shaft 31 is provided having a crank arm 32 which carries a connecting rod 33, said connecting rod being connected to a

piston 34 by means of a pin 35. A gear 36 55 is mounted upon the crank shaft 31, which is adapted to cooperate with an oil throwing gear 37 for the purpose of throwing oil which is contained within the lower part of the crank case 21, to the moving parts 60 within the crank case and also the piston.

A passage 38 is provided in the crank case 21 which leads into a breather tube 39, the construction of which is clearly described in my above mentioned co-pending 65 application. Breather tube 39 is in direct communication with a casting 40, serving as the end cover for the breather tube and provides a passage from the breather to the intake passage 26, whereby communication is 70 obtained between the crank case 21 and the explosive chamber 25.

The entrance to the breather tube passage is exposed to the direct action of the splashing within the crank case, and to prevent the passage of oil out through the 75 breather tube passage, the entrance into the passage 38 from the crank case 21 is provided with a baffle 41 which consists of a plate provided at one end with tongues 42 80 and 43, at its sides with flanges 44, and with a tongue 45 along the other end, said tongues and flanges cooperating with a shoulder formed by the junction of the breather passage and crank case to hold the 85 baffle 41 in position. Apertures 46 are provided and are formed by punching out and bending over members 47 which then act as deflectors to deflect oil, which is splashed by the crank arm and oil throwing gear, thereby preventing it from passing through the 90 passage 38. It will be observed that the deflectors which are arranged at an angle to the breather tube passage not only break up the moving oil-laden air but also deflect it 95 laterally as it enters the passage, thereby suddenly changing its direction of movement and tending to throw down or separate out the particles of oil which then flow back into the crank case by the most convenient path.

When the baffle is formed, the tongue 42 is parallel to tongue 45 and the deflectors 47 so that it can easily be located in the desired position. While the engine is being assembled, the baffle can be placed within the opening into the passage 38 by reaching 100 through the opening in the crank case which,

is afterward covered by end cover 21*; and then by reaching through at the upper end of the passage 38, before the breather tube is in position, the tongue 42 can be bent into 5 a holding position.

It will be apparent from the foregoing description, that the quantity of crank case lubricant which enters the combustion chamber will be reduced to a very small value by 10 means of the present invention. The baffle prevents the direct splashing of excessive quantities of oil into the passage 38, and also separates to a large degree the oil mist from the air which is forced out of the 15 crank case by the action of the piston. The result is that very little crank case oil will enter the combustion chamber to form a carbon deposit.

While the forms of mechanisms herein 20 shown and described constitute a preferred embodiment of one form of the invention; it is to be understood that other forms might be adopted, and various changes and alterations made in the shape, size and proportion 25 of the elements therein without departing from the spirit and scope of the invention.

What I claim is as follows:

1. In an engine of the character described, in combination, an engine cylinder, a crank 20 shaft, a piston in the cylinder, a connecting rod for the piston and crank shaft, a crank case for housing the crank shaft, said crank case having an obliquely disposed upper side wall connected to the cylinder at its upper 30 end and having a passage extending therethrough in the plane of rotation of the crank, and a baffle arranged inside said crankcase and across the mouth of said passage and in the plane of said obliquely disposed wall.

2. In an engine of the character described, in combination, an engine cylinder, a crank 35 shaft, a piston in the cylinder, a connecting rod for the piston and crank shaft, a crank case for housing the crank shaft, said crank case having an obliquely disposed upper side wall connected to the cylinder at its upper end and having a passage extending therethrough in the plane of rotation of the 45 crank, a baffle disposed across the mouth of said passage and in the plane of said obliquely disposed wall, and tongues at opposite ends of said baffle for removably holding the same in position.

3. In an engine of the character described, in combination, an engine cylinder, a crank 50 shaft, a piston in the cylinder, a connecting rod for the piston and crank shaft, a crank case for housing the crank shaft, said crank

case having an obliquely disposed upper side 60 wall connected to the cylinder at its upper end and having a passage extending therethrough in the plane of rotation of the crank, a baffle disposed across the mouth of said passage and in the plane of said 65 obliquely disposed wall, and means including a plurality of tongues at one end of the baffle for engaging the interior walls of the crank case and said passage to hold the baffle in position.

4. In an engine of the character described, in combination, an engine cylinder and cylinder head having an engine intake passage, a piston in the cylinder, an engine crank case containing a lubricant adapted to be splashed about therein, a crank shaft journaled therein, a connecting rod for the piston and crank shaft, a breather passage through the wall of the crank case and connecting the interior thereof with the intake passage, and 75 a baffle located inside said crankcase and within the opening leading therefrom into 80 said breather passage.

5. In an engine of the character described, in combination, an engine cylinder, a crank 85 case therefor, a breather passage through the wall of the crank case, a baffle for the breather passage arranged inside the crankcase and within the opening leading therefrom into said breather passage, said baffle 90 having a plurality of tongues on its peripheral edge for holding the baffle in operative position.

6. In an engine of the character described, in combination, an engine cylinder, a crank 95 case therefor, a breather passage through the wall of the crank case, a baffle for the breather passage, said baffle having tongues at opposite ends thereof and adapted to engage the wall of the crank case for holding 100 the baffle in position.

7. In an engine of the character described, in combination, an engine cylinder, a crank 105 case therefor, a breather passage through the wall of the crank case, a baffle for the breather passage, said baffle having tongues at opposite ends thereof and upturned flanges at the side edges thereof adapted to engage said crank case and said breather passage for holding the baffle in operative 110 position.

In testimony whereof I affix my signature.

CHARLES F. KETTERING.
